UNITED STATES PATENT OFFICE.

ARTHUR ISAAC BLANCHARD, OF UPPER CLAPTON, LONDON, ENGLAND.

LIQUID-HYDROCARBON-VAPOR BURNER.

1,129,783.

Specification of Letters Patent. Patented Feb. 23, 1915.

Application filed April 15, 1912. Serial No. 690,816.

To all whom it may concern:

Be it known that I, ARTHUR ISAAC BLANCHARD, engineer, a subject of the King of Great Britain, residing at No. 2 Chardmore road, Upper Clapton, London, England, have invented certain new and useful Improvements in or Relating to Liquid-Hydrocarbon-Vapor Burners, of which the following is a specification.

This invention relates to liquid hydrocarbon vapor burners or the like of the class or type in which the liquid hydrocarbons are supplied under pressure to a vaporizer or chamber where the same are vaporized, and the vapor issues (under pressure) as a jet through a fine orifice into a mixing tube or chamber where it draws in and is mixed with air and then burnt on the well-known Bunsen principle; with means to clean or clear the said fine jet orifice.

This invention consists specifically in certain improvements applied to the spindle that controls the operation of the burner. This spindle carries a needle clearing device, adapted to operate to clear the jet orifice when necessary, and carries further a valve for controlling the supply of vapor to the jet orifice. The two improvements are, first, improved means for mounting said spindle in its casing in a gas tight and oil tight manner by means of a metallic bellows, at the same time permitting reciprocation of the spindle to operate the clearing needle when clearing is necessary; second, a thermal locking device for the spindle, carrying an easily fusible metal as an operating medium. This thermal lock is adapted to lock the spindle in the closed position of the controlling valve after the valve has been closed, and the burner extinguished, and the fusible metal cooled sufficiently. This thermal lock is released and the above mentioned bellows allowed to move the spindle to the open position of said valve, when the apparatus has been heated up hot enough by any well known external means, to melt this fusible metal.

In the accompanying drawings I have illustrated two examples of the present invention as carried into practice in conjunction with a spindle carrying thereon at one end or toward one end a needle clearing device as well as a valve for regulating the supply of vapor. At the other end said spindle is attached to a thin metal sheet which is provided with several folds form-

ing an expandible and collapsible metal box or metal bellows the latter being closed at one end and at its other end connected in an oil tight manner (for example by means of a screw union) with the casing of said spindle.

Referring to the accompanying drawings:—Figure 1 is a view of the burner—partly in elevation but mainly a vertical longitudinal sectional view—arranged for use in a lamp of the inverted incandescent type. Fig. 2 is a plan of the burner. Fig. 3 is a vertical sectional view—on an enlarged scale—of the means for automatically locking and unlocking the valve spindle. Fig. 4 is a similar view to Fig. 3 but taken at right angles thereto. Fig. 5 is a view in elevation of a standard lamp with a burner in accordance with the present invention. Fig. 6 is a view partly in elevation and partly in longitudinal section of a modified construction of the burner arranged for heating purposes *i. e.* for use in a heating stove. Fig. 7 is a plan of the heating stove in accordance with the present invention—as shown in Fig. 6. Fig. 8 is a sectional view showing a modification as hereinafter described.

Referring now more particularly to Figs. 1, 2 and 5: The clearing needle or clearing device (which may be of any known or suitable kind such as a fine flexible point A) is mounted at the end of a spindle or rod B adapted to slide in a sleeve C in alinement with the jet orifice D (which latter may be of any known or suitable kind) the said spindle B and sleeve C being of sufficient length to insure that the ends thereof further from the needle A are well away from the heat. That end of the spindle B nearest the needle may carry, or be formed as the valve E, for example said end may be turned conical so as to be adapted to act as a valve E when pressed endwise on a suitable seating F formed in the sleeve or casing C.

One end of the sleeve C is attached to the burner in such a way that it communicates directly with the passage G, leading to the jet orifice D. On the other end is screwed the collar C', onto which is screwed in turn, at M', the flanged ring M. A spring bellows H, made of suitable flexible metal, is attached in a firm and oil tight manner to said ring M, by soldering for example. The spindle B passes through the central part of the bellows H, being fixed thereto in an

oil tight manner. Such an oil tight connection may be effected by reducing the spindle at the point where it passes through the bellows, thus forming a shoulder B^2 .
5 A nut N is then screwed onto the spindle, so as to press the metal around the periphery of the aperture through the bellows, tight up against the shoulder B^2 . Or the periphery could be soldered against the said shoulder, if desired. This structure permits reciprocation of the spindle within the sleeve, and yet allows no escape of oil or vapor from the sleeve. A knob is mounted on the outer end of the spindle B , for 10 manual actuation of the spindle. If the jet orifice should happen to clog up, the knob is pressed inward a few times, which pushes the needle into the jet orifice. The spindle springs back to the right after each application of pressure, by virtue of the spring of the bellows, and the vapor pressure acting on the inside of the bellows. Further means of compressing said metal bellows H are also provided for the purpose of forcing 15 the valve E on said spindle B tightly upon its seating F to cut off the vapor supply and extinguish the flame. Such further means comprises for example a screw cap L adapted to completely inclose said metal bellows H . Said screw cap L being internally screw-threaded and adapted to screw onto an externally screw-threaded flange M rigidly fixed, formed or mounted on the aforesaid sleeve or casing C . For example the outer 20 end of the aforesaid sleeve C may be provided with a screwed union $C^1 M^1$ on one part M^1 of which union the said externally screwed flange M is carried. It will be obvious that this arrangement of metal bellows H upon the end of the aforesaid spindle B and means of operating said metal bellows may be employed in conjunction with a spindle carrying or operating a valve such as E only or carrying or operating a 25 needle clearing device such as A only or carrying or operating both the valve E and needle clearing device A as illustrated.
The following is an example of that part of the present invention relating to the 30 means for automatically locking and releasing the valve spindle B as carried into practice with a valve spindle such as B reciprocated endwise either in the manner above described or in any other suitable manner.
55 Referring more particularly to Figs. 1 to 5:—On or in connection with the valve spindle casing C at a suitable point (where it will be adapted to be readily heated) there is provided a suitable vessel such as a 60 small cup O containing fusible metal O^1 into which latter extends a rigidly fixed pin P (e. g. as hereinafter described). The lower end of the said cup O is arranged and adapted to engage in or with the said 65 spindle B , for example, arranged to engage

in a recess or groove (such as a circular groove B^x) in the said spindle B for which purpose the lower end of said cup O may be formed with a semi-circular shaped recess O^2 which straddles the reduced diameter of the spindle B in between the shoulders formed by said circular groove B^x in said spindle. By this arrangement, when the valve E has been forced or screwed upon its seating F and the flame extinguished 70 and the easily fusible metal O^1 allowed to cool, this said spindle B and valve E will be locked with the valve in the closed position the cup being held rigid by the now solid metal O^1 and fixed pin P therein. 75 When it is desired to start up the burner the screw cap L is slackened back or screwed back so that the spindle B will then be held locked in position with the valve E tight upon its seating F by means only of the 80 aforesaid solid metal O^1 in the cup O until the burner is again heated up at starting and becomes sufficiently hot whereupon such metal O^1 fuses and thereupon the spindle B is released and the valve E thereby opened 85 automatically. The aforesaid fixed pin P , in the arrangement illustrated is fixedly carried in the screw plug Q provided with an external polygonal sided head Q^1 to enable said plug to be screwed into a dome or upright extension R on the exterior of and in communication with the interior of said casing; which dome or upright extension R and plug Q therein inclose the movable cup O in an oil-tight manner. It will be obvious that this arrangement of fusible metal 90 O^1 in the cup O or equivalent with a fixed pin P or equivalent extending into said metal may be employed in any other suitable manner according to the burner employed or the position assigned to this device as for example with the device above the said valve spindle B the pin P is fixed and the cup O movable as aforesaid; or with the device arranged below the valve 95 spindle B the cup (containing the fusible metal) would be fixed below said spindle and the pin would be movable and extend into the fusible metal at its lower end while its upper end would engage in or with the 100 spindle B .
105 I will now proceed to describe the present invention as carried into practice with an inverted burner in connection with which an incandescent inverted mantle is employed. 110

115 The liquid hydrocarbon may be supplied under pressure to a suitable vaporizing chamber of the known type such as the vaporizing chamber S ; and from such vaporizing chamber S the vapor is led to the interior of the casing C in which the aforesaid spindle B is adapted to be longitudinally reciprocated in the aforesaid manner. The said spindle B in the arrangement illustrated carries both the valve E and needle 120 125 130

clearing device A thereon; and in conjunction with which spindle B there is shown in the accompanying drawings the aforesaid automatically acting means to lock this said 5 valve spindle B in the closed position when the fusible metal is cooled and to release said valve spindle when the burner is hot during its operation, said valve spindle being advantageously arranged parallel with 10 and just above the horizontal vaporizing chamber S before referred to.

From the jet orifice D the vapor issues as 15 a jet past laterally opening air supply passages T^x into a double conical chamber U^1 i. e. the walls of said chamber at U^1 first converge in the direction of the jet so as to form a reduced or constricted passage at U^2 and from this point the walls U^2 diverge to the full bore of a bent tube V through 20 which the mixture of vapor and air is led into a downwardly extending chamber W with burner nozzle of any suitable type said chamber being advantageously provided with one or more horizontal partitions of 25 wire gauze as also is the burner nozzle on which latter the incandescent mantle X is mounted or carried.

The arrangement for admitting the air supply to the vapor jet as illustrated in the 30 accompanying drawings is as follows:—At a point along said sleeve or casing C at a suitable distance from the point of burning (e. g. about midway between the jet orifice D and the aforesaid metal bellows H on 35 the end of said spindle B) there is arranged an air admission chamber as for example a circular metal box T mounted upon and surrounding the aforesaid sleeve or casing C of the spindle with a suitable number of 40 holes or openings for the outside atmosphere to pass into said box T; and from the latter two metal tubes T^1 and T^2 one on each side of the spindle B and parallel thereto lead the air (by means of an elbow 45 T^x at the end of each) to the lateral openings or passages (before referred to) located on opposite sides of the jet orifice D, the point where these air tubes admit the air on 50 opposite sides of the jet being located advantageously centrally or thereabout over the burner. The aforesaid air admission box or chamber T thus serves to cool or assist in cooling the sleeve or casing C inclosing the valve spindle D.

55 For the purpose of conducting heat or assisting in conducting heat to the vaporizer chamber S and its connection, a horizontal circular plate Y with a central opening Y^1 therethrough may be mounted on 60 said vaporizer and located just above the burner chamber W.

A suitable shield or casing is or may be provided for inclosing the more highly heated parts of the burner as for example a 65 cylindrical metal casing Z (Fig. 5) may be

employed which, as shown, does not inclose the aforesaid automatic means for locking and releasing the valve spindle but the latter may be arranged to be inclosed therein if desired, the aforesaid air admission box T 70 being located exteriorly of said casing Z which latter may be provided if desired with a conical or other suitably shaped dome or top Z^1 having a central opening through which opening the products of combustion 75 can pass.

At each operation of the jet orifice clearing device the supply of vapor is momentarily interrupted and consequently the flame extinguished and in the case of the 80 employment of the burner in conjunction with any incandescent mantle for lighting purposes as illustrated for example in Figs. 1 to 5 this extinction does not matter as the 85 said mantle being incandescent will remain so long enough to re-light the vapor as same is supplied again after each momentary clearing operation and consequential momentary extinction of the lamp.

Referring now more particularly to Figs. 90 6 and 7:—These figures illustrate a burner for heating purposes having my present improvements applied thereto. In these Figs. 6 and 7 the letters of reference indicate corresponding parts to those described with 95 reference to Figs. 1 to 5:—The vaporizer chamber S as illustrated in Figs. 6 and 7 is vertically arranged with the lower end thereof supported direct upon the reservoir 100 S¹ to thus support the burner, the exterior of said vaporizer chamber S carrying the pan S² for starting the burner. At its upper end said vaporizer chamber S is in oil tight connection with the interior of the casing C the conduit V for conducting the 105 gaseous mixture to the burning point terminating in the perforated end V^1 which latter is located in the open topped metal pan W¹ which latter becomes highly heated 110 when the burner is in operation and by conduction the necessary heat passes from said pan W¹ to the vaporizer S.

In Fig. 8 there is illustrated a modification showing the movable cup O (containing the easily fusible metal O¹) and its 115 casing R and adjuncts arranged just over, and in vertical alinement with, the vertical part S of the vaporizer tube or chamber. This arrangement of the cup O and its casing R in vertical alinement with a vertical tube S has the advantage that it enables access to the vertical tube to be obtained through the casing R, by removing the cup O and withdrawing the spindle B; and this obviates the necessity of forming the lower 120 part of said tube S detachable and thereby saves the joint in the latter as shown in Fig. 1, i. e. this arrangement in Fig. 8 enables said vertical tube S to be made jointless. Furthermore this arrangement of the cup O 125 130

and its adjuncts as shown in Fig. 8 (in vertical alinement with the vertical tube S) has the advantage of bringing said parts O O¹ P and R under the hood or casing Z or enabling same to be more or less inclosed by such casing Z. The inclosing of the casing R in the hood or casing Z in either of the above-named manners (or in any other suitable manner) is or may be advantageous for some purposes as for example where the burner is to be used under conditions of exposure to cold or cold winds or such like conditions.

What I claim is:—

1. In a vapor burner, the combination with a valve spindle, of a valve controlled thereby, adapted to open and close the vapor passage from the generator to the burner, manually-actuated means to move said spindle into the closed position of said valve, and thermally-operated locking means adapted to hold said spindle in this position.

2. In a vapor burner, the combination with a valve spindle, of a valve controlled thereby, adapted to open and close the vapor passage to the burner, manually-actuated means to move said spindle into the closed position of said valve, means to move said spindle into the open position of said valve, thermally-operated locking means adapted to hold said spindle at the closed position of said valve after the extinguishment of the burner, and further adapted to release said spindle and permit said opening means to open said valve when a certain temperature is reached in the burner.

3. In a vapor burner, the combination with a casing, of a spindle movable longitudinally therein, a valve controlled by said spindle, a metal bellows attached to one end of said casing by means of a fluid tight connection, said spindle adapted to pass through said bellows in a fluid tight connection, and a thermally-controlled lock for said spindle adapted to hold said spindle in the closed position of said valve after the extinguishing of the flame, and to release said spindle to permit said bellows to move the spindle to the open position of said valve, when a certain temperature has been reached in the burner.

4. In a vapor burner, the combination with a casing, of a spindle movable longitudinally therein, a valve controlled by said spindle, a metal bellows attached to one end of said casing by means of a fluid tight connection, said spindle adapted to pass through said bellows in a fluid tight connection, a thermally-controlled lock for said spindle adapted to hold said spindle in

the closed position of said valve after the extinguishing of the flame, and to release said spindle to permit said bellows to move the spindle to the open position of said valve, when a certain temperature has been reached in the burner, and means mounted on said casing engaging with said spindle, adapted to be set to hold the spindle in the closed position of said valve while the thermal lock cools sufficiently to hold the spindle in this position.

5. In a vapor burner, the combination with a spindle, of a vapor valve controlled thereby, a thermally-controlled lock for said spindle comprising a cup, containing a fusible substance, engaging with said spindle, a casing loosely inclosing said cup, a member carried by said casing projecting into said fusible substance, said lock when cool being adapted to hold said cup and spindle rigidly, while when heated and fused, adapted to permit free movement of said cup and spindle.

6. In a vapor burner, the combination with a casing, of a spindle longitudinally movable therein, a valve controlled by said spindle through such longitudinal movement, a cup containing a fusible substance engaging with said spindle, a fixed member projecting into said fusible substance adapted to lock said spindle against movement when cool, and to permit movement thereof when heated and fused, and a bellows engaging with said casing and said spindle by means of fluid tight connections, adapted to permit longitudinal movement of said spindle, said bellows adapted to move said spindle to the position thereof to open said valve.

7. In a vapor burner, the combination with a vapor valve, of thermal controlling means therefor, comprising a cup containing a fusible substance engaging with said spindle, a fixed member projecting into said fusible substance, said thermal controlling means being within the zone of heat from the burner, and adapted to lock said spindle when the temperature of the burner and fusible substance fall below a certain point, and adapted to release said spindle when such temperature goes above this point, and means for automatically moving said spindle to the open position of said valve upon release of the spindle by said thermal-controlling means.

In witness whereof I have hereunto set my hand in presence of two witnesses.

ARTHUR ISAAC BLANCHARD.
